UNITED STATES PATENT OFFICE.

KENNETH P. ROWE, OF NEW YORK, N. Y.

FIRE APPARATUS.

No. 921,284.

Specification of Letters Patent.

Patented May 11, 1909.

Application filed September 11, 1908. Serial No. 452,589.

To all whom it may concern:

Be it known that I, KENNETH P. ROWE, a citizen of the United States of America, and a resident of New York city, New York, 5 have invented a new and useful Improvement in Fire Apparatus, which improvement is fully set forth in the following specification.

This invention relates to fire-apparatus 10 comprising a set of buckets nested in one another within a tank filled with water or other fire-extinguishing liquid. In such bucket-and-tank apparatus it is essential that the buckets can be instantly removed, without 15 the slightest delay; that the buckets stand filled, ready for instant use; that the handle or bail of each bucket shall be in position for instant grasping by the attendant; that the evaporation of the water or other liquid be 20 prevented; and that there be no tendency to rusting or corrosion of the metallic parts which might cause the nested buckets to adhere one to another or to the tank that contains them. In the next place, it is desir- 25 able that the buckets may be readily inserted in place and "centered", and that the column of nested buckets be maintained in its proper vertical alinement against any tendency to topple over. This latter is par- 30 ticularly necessary in case the bucket-and-tank apparatus be employed on ship-board where the tilting of the deck tends to cause the pile of buckets to topple and become dis- 35 arranged.

The object of my invention is to obtain the results above indicated.

The invention consists firstly, of spacing- 40 rests carried by each bucket to support the next bucket in the series, which rests are so constructed and arranged as to act as "cen- 45 tering devices" for guiding the next bucket into position and for maintaining it level; secondly, in means for guiding the lower- 50 most bucket into its position centrally of the tank, and for maintaining it there; thirdly, in means for maintaining the uppermost 55 bucket in proper vertical alinement; and, fourthly, in a novel construction of the cover of the tank, which preferably comprises the upper alining-means last referred to.

The invention consists further in combi- 55 nations of two or more of the foregoing fea- tures; and in the various details of con- struction and arrangement hereinafter more particularly pointed out and claimed.

Referring to the drawings annexed here-

to that illustrate a preferred form of my invention, Figure 1 is a vertical section through a tank, with its cover, containing six nested buckets; Fig. 2 is a plan view of a cage con- 60 stituting a preferred device for centering and maintaining the lower bucket; Fig. 3 is a plan view of a bucket containing three of the spacing-rests referred to; Fig. 4 is a detail of a preferred form of spacing-rest; and Fig. 65 5 is a detail of the cover.

1 represents the tank. 2 is its cover, hinged thereto in any convenient manner, and provided with a suitable latch if desired.

3, 3', 3'' represent the buckets, here shown 70 as six in number.

Upon the floor of the tank rests a ring (or annular plate) of metal 4, whose diameter is substantially that of the bottom of the buckets 3. 5 is a larger metal ring fitting snugly 75 within the top of tank 1. Substantially- vertical rods 6 connect the two rings 4 and 5. These rods are shown as three in number. Each of these rods has an inclined off-set 7, above which they extend as shown, to the 80 upper ring 5; while below this off-set (at 8) they incline inwardly parallel to the flare of bucket 3, so as to provide a cage within which the bucket fits easily. A bucket may be dropped hap-hazard into the tank, and 85 the inclines 7 and 8 will guide it into the proper position, and then maintain it there.

9 represents the handle or bail, indicated as secured to the bucket by ears 10 (this construction being set forth in Rowe's U. S. 90 Patent No. 875,289, dated Dec. 31, 1907.)

The off-sets 7 in the rods 6 leave room for the bails 9. This cage (formed of the rods and rings) may be used interchangeably in different tanks. Instead of ring 4, a solid 95 plate or disk may connect the bottom of the rods 6; and, indeed, instead of the cage I may provide upon the floor of the tank, merely a circular rib or other centering device for the bottom of the lower bucket 3. 100

Inside each bucket 3—3' etc. and near the bottom thereof, are the spacing-rests 11, here shown as three in number. These rests differ in construction and in function from the somewhat similar rests shown in Leon- 105 ard's U. S. Patent No. 498,937 (dated June 6, 1893). My novel rests are shown as formed each of a strip of metal bent into the form of a V and having the wings 12—12 for securing it to the bucket 3; and with its mid- 110 dle, or V-portion, cut away to present the inclined edges 13—13, and the horizontal

edges 14—14. The inclines act as guides for centering the next upper bucket, the outer rim of whose bottom rests upon edges 14 and fits into the angles 15 formed by the 5 respective meeting-edges 13 and 14. That is, these angles 15 all lie in the same horizontal plane, and in a circle equal in diameter to the bottom of the bucket. If a bucket as 3' be placed without any particular care into 10 another bucket 3 of the series, the inclined faces 13 will guide it into the proper central position upon the seats 14, while angles 15 hold it out of contact with the lower bucket 3, so that there is little or no tendency for 15 any two buckets to become corroded together. Instead of forming the spacing- rests of sheet metal as shown, they may be of any other construction so long as at least three fixed points of support are provided, 20 together with inclines for guiding the bottom of another bucket to the seats and maintaining it there.

The cover 2 of the tank is shown as punched up of a single sheet of metal in such 25 manner as to provide the crown 16 and a substantially horizontal flange 17 whose outer end is slightly inturned as at 18; and in the recess thus formed is located a gasket 19, of rubber or the like, adapted to rest upon 30 the rim 20 of the tank. 21 is a collar or band of metal secured within the crown and depending into the mouth of the tank. It will be noticed that the pocket or cavity containing the gasket 19 opens downwardly, 35 so there is no chance to retain any moisture. The collar 21 may extend straight down, as in the cover of an ordinary tin bucket; but preferably it converges, funnel-wise, downwardly and inwardly, as at 22, to fit snugly 40 within the top of the uppermost bucket 3". Instead of this funnel-like arrangement, a 45 boss or other depending device may be secured within the cover 2 to engage the top of the uppermost bucket 3" and maintain the vertical alinement of the nested buckets.

There is considerable contact surface between the gasket 19 and the rim 20 of the tank (the two being preferably some fifteen inches in diameter), so that after the device 50 has stood unused for a long while, they are liable to stick together; and, at last, when the cover is lifted there is danger of the gasket adhering to the rim and leaving its proper seat. To prevent this, I provide the 55 gasket with a plurality of inwardly-disposed lugs 23, that extend through suitable slots in the metal collar 21. If desired, a pin 24 or other device may be employed as a positive fastener, or the tightness of the fit with 60 lugs 23 may be relied on.

By reason of the cage (consisting of the rods 6 etc.) or its equivalent, the spacing- rests 11, and the upper device 22, the buckets are readily and properly positioned; they 65 are maintained securely with their bottoms

in a horizontal position or leveled and with the buckets themselves in vertical alinement without any danger of toppling; their handles are permitted to lie in position for instant grasping when necessary; and there is 70 the minimum of contact of metal upon metal, and the minimum chance of buckets corroding together. While the construction and arrangement of the gasket renders the device 75 always ready.

Parts of my invention may be employed to the exclusion of other parts, and modifications may be made in the construction and arrangement of the various parts, without in any case departing from the spirit of my invention. 80

Having thus described my invention, I claim:

1. In a bucket-and-tank apparatus, the combination with the tank and the nested buckets, of centering-means for positioning the lowermost bucket within the tank, other centering-means for positioning and leveling each bucket within the next lower one, and further means carried by the cover of the 90 tank for maintaining the topmost bucket in alinement.

2. In a bucket-and-tank apparatus, the combination with the tank and the nested buckets, of centering-means for positioning 95 the lowermost bucket at any axial position within the tank, and other centering-means for positioning and leveling each bucket at any axial position within the next lower one.

3. In a bucket-and-tank apparatus, the 100 combination with the tank and the nested buckets, of centering-means for positioning and leveling each bucket within the next lower one, and means carried by the cover for maintaining the topmost bucket in alinement. 105

4. In a bucket-and-tank apparatus, the combination with the tank and the buckets nested therein, of centering-means for positioning the lowermost bucket, and means 110 carried by the cover for maintaining the topmost bucket in alinement.

5. In a bucket-and-tank apparatus, the herein-described spacing-rests consisting of 115 three or more seats secured on the inner side of each bucket in the same horizontal plane, each seat having a horizontal portion and an outwardly-inclined portion leading upward therefrom to the wall of the bucket, the several angles formed by the said portions outlining a circle of the same diameter as the bottom of said bucket. 120

6. The combination with a fire-bucket, of a spacing-rest therein consisting of a V-shaped strip of metal secured thereto and 125 having the V-shaped portion cut away to provide inclined edges and horizontal edges meeting at an angle.

7. The combination with a bucket-and- 130 tank apparatus, of a detachable and inter-

changeable bucket-cage comprising a plurality of substantially-vertical rods held in fixed position at their tops and bottoms.

8. In a bucket-and-tank apparatus, the combination with the tank, of a bucket-cage located within the tank and comprising a plurality of substantially-vertical rods whose upper ends are held in position against the upper part of the tank and whose lower ends 10 incline inwardly to form a bucket-seat.

9. In a bucket-and-tank apparatus, the combination with the tank, of a cover therefor having a depending flange converging inwardly, whereby the top of the uppermost of 15 a series of nested buckets may be engaged.

10. In a bucket-and-tank apparatus, the combination with the tank, of a cover therefor having its lower end flanged outwardly and then inwardly to form a seat, a collar se-

cured within said cover and converging 20 downwardly and inwardly whereby the top of the uppermost of a series of nested buckets may be engaged and a gasket held between said flange and said collar to rest upon the rim of the tank.

11. In a bucket-and-tank apparatus, the combination with the tank, of a cover therefor having a downwardly-opening seat opposite the rim of the tank, and a gasket of rubber or the like located in said seat and having 25 30 holding-ears engaging said cover.

In testimony whereof I have signed this specification in the presence of two subscribing witnesses.

KENNETH P. ROWE.
